UNITED STATES PATENT OFFICE.

PAUL STONER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

CROWNING DEVICE FOR ROLL-GRINDING MACHINES.

Application filed February 25, 1926. Serial No. 90,641.

My said invention relates to a crowning and concaving device for roll grinding machines and it is an object of the same to improve the action of a grinding wheel in producing concave or convex surfaces on cylindrical work with particular reference to such work as mill rolls of the sort used in steel mills.

Referring to the accompanying drawings 10 which are made a part hereof and on which similar reference characters indicate similar parts,

Fig. 1 is a side elevation of the machine showing the general arrangement of the 15 wheel base with the grinding wheel in contact with the work,

Fig. 2, a front elevation of a roll with a concave surface.

Fig. 3, a sectional front elevation of the 20 wheel base showing the general arrangement of the mechanism for crowning or concaving a roll,

Fig. 4, a sectional side elevation of the 25 gear change for the lifting cams,

Fig. 5, an end view of the wheel base showing the grinding wheel in a position below the work center, i. e., a horizontal plane passing through the axis of the work,

Fig. 6, an end view of the wheel base 30 showing the grinding wheel in position above the work center,

Fig. 7, a detail of parts shown in Fig. 1 on a much enlarged scale.

Figure 8, a side elevation of the machine 35 with certain parts broken away to show the internal structure, and

Figure 9, a partial plan view of the machine with certain parts broken away to show the internal structure of the machine.

40 In the drawings reference character 10 indicates the fixed bed or base of the machine which provides a support for the working parts. A support 11 is movably mounted on the base and is provided with means of 45 any suitable or conventional character for supporting and rotating the work 12, here shown as consisting of a mill roll of the character above referred to.

At the rear of the work holding devices 50 the bed is provided with a wheel carriage 13 which may be generally similar to that shown in my copending application No. 681,607, filed December 19, 1923, now Patent No. 1,609,217, being provided with suitable 55 means for moving it lengthwise of the work

along guides 13' of the bed. Said carriage includes a bracket 14 connecting it to an auxiliary carriage 15 movable on the bed with the main carriage, this auxiliary carriage supporting a motor 16 for driving the 60 wheel 17.

The rotor of the motor is connected to the shaft 18 of the grinding wheel by means of a belt 19 passing over a pulley 20 on said wheel shaft, said belt also passing over an 65 idler 21 by means of which the tension of the belt may be adjusted and over a pulley 22 on a shaft 23. The shaft 23 carries a sprocket connected to another sprocket 23' (Fig. 3) on a shaft-section 24 by means of 70 a sprocket chain 25 for driving the shaft 24. The shaft-section 24 is connected by a flexible coupling 31 to a shaft-section 32, which in turn is connected by a flexible coupling 33 to a worm, said worm driving 75 the reversing mechanism for the wheel carriage. A shaft 28, has at its lower end a gear 56 which engages a spiral gear 57 on a shaft 58. The shaft 58 has a worm 63 fixed thereto which engages the fixed rack 26 80 (Fig. 1) and so drives the traversing carriage by way of the train of mechanism described. The last-named parts are protected by a gear casing 30. A slide base 34 is supported on the reciprocating carriage 13 for 85 movement toward and from the work. The slide base is provided with means (not shown) by means of which it may be moved quickly into and out of operative position 90

95 A sub-base 35 is supported on the slide base by means of guides 36 for adjustment of the wheel to set the same in proper operative relation to the work and to compensate for wear. A wheel base 37 is pivoted at 38 on the sub-base 35 and the wheel base may be moved about the pivot in order to bring the wheel temporarily out of relation to the work and in order to produce a crowning or concaving effect on the work or to vary the 100 same.

The wheel base is provided at its forward end underneath the grinding wheel shaft with rollers 39 adapted to act as followers for either pair of two pairs of cams 40 and 41 arranged along a cam shaft 42. For moving the followers into operative relation with either one of said cams I have provided means comprising a shaft 43 journaled in the wheel base and carrying at opposite 110

ends sleeves 44 with helical cam grooves 45 at their inner ends. These sleeves are splined to the shaft 43 which is provided with a lever 47 for rotating it. Followers in the 5 form of pins 48 fixed to the wheel base engage the cam grooves 45 in the sleeves. It will be obvious from this that when the shaft 43 is rotated in one direction or the other the sleeves will turn with it and the 10 cam grooves will force the sleeves to move lengthwise of the shaft so as to carry the followers 39 from the cams 40 to the cams 41, or vice versa, the position of the lever for concaving being indicated in full lines in 15 Fig. 7, while that for crowning is indicated in broken lines.

The followers 39, of course, cannot well move from one cam to the other without first being lifted off the cams. For this purpose a pair of blocks 49 are provided adjacent the inner ends of the sleeves and these blocks are fast to a shaft 50 which also bears a handle 51 for operating the blocks. When the followers are to be moved from one cam 20 to the other, the cam shaft is turned to a position where the base is raised sufficiently so that the support blocks can be brought to their lowermost position by turning the lever 51, without interference with the movement of said blocks. When this has been 25 done the wheel base is lowered, so as to put the weight of the wheel base on the blocks. When the cam shaft is now turned further, the cams will be relieved of the weight of 30 the rollers and the followers can be shifted from one set of cams to another. It will be understood from Figure 7 that the support blocks 49 and the lever 51 have been moved in this operation from the solid line 35 position of the lever and the heavy broken line position of the support blocks to the light broken line position of the support blocks and the corresponding broken line 40 position of the lever.

45 The sleeves 44 having now been actuated to bring the followers out of operative relation to one set of cams and into operative relation with the other, the cam shaft is now turned again to lift the weight of the 50 wheel base off the support blocks, whereupon these may be moved from the position shown in light broken lines to the position in heavy broken lines by an operation the reverse of that first described.

55 In grinding convex rollers the wheel base is moved on its pivot 38 to move the line of contact between the wheel and the work from a point above a horizontal plane passing through the axis of the work and the pivot of the wheel-base to a point below such plane and back again. This change of relation is produced by means of the cams 40 and 41 acting on the followers 39 as the shaft 42 rotates. To produce such action the shaft 60 42 is driven by means of a worm wheel 52

meshing with a worm gear 53 on a shaft 54. The shaft 54 is operated by change speed gearing shown in detail in Fig. 4 which change speed gearing is driven in timed relation with the carriage reciprocating 70 mechanism by means comprising the shaft 28 (Figs. 1 and 3), gear 56, gear 57 on shaft 58, beveled gears 55 and 59 located respectively on shafts 58 and 60, a beveled gear 59 on shaft 60 and a beveled gear 61 on 75 a shaft 62 which is the drive shaft of the change speed gearing.

The change speed gearing comprises a drive shaft 62, a back gear 64, and an intermediate shaft 65. The drive shaft and intermediate shaft have gears meshing with each other in constant relation and the back gear shaft has a shiftable gear 66 adapted to be moved into engagement with either of the two gears 67 and 68 on the drive shaft 80 by means of a shifter 69.

A gear 70 on the intermediate shaft is adapted to be placed either on this shaft or on the back gear shaft, said gear meshing with a gear 71 and gear 71 may also be placed on either shaft 64 and 65, the gear 70 being then located on shaft 62. The intermediate shaft carries a gear 72 movable into and out of engagement with a gear 73 on a shaft 54 by means of a shifter fork 75 90 operated by a lever 76, Fig. 1. By moving this lever the change gearing is disconnected which places the crowning and concaving means out of operation, as for grinding straight rolls, by disengaging gear 72 from gear 73 splined to shaft 54. This gear 73 is splined to shaft 54 for driving said shaft and this shaft also has a worm 53 fixed thereto which drives the worm gear 52 on the cam shaft 42 at a speed determinable by 95 the arrangement of the change speed gearing.

With the gear 66 in the position indicated in solid lines in Fig. 4 and with the gear 70 in the position indicated in broken lines 100 low speed will be obtained, the drive being from shaft 63 through gears 71, 70, shaft 64, gears 66, 67, 77, 68, 78, shaft 65 and gears 72 and 73 to shaft 54. By moving gear 66 to the position indicated in broken lines, 115 leaving gear 70 in the broken-line position, intermediate speed will be obtained through a train comprising a shaft 62, gears 71, 70, shaft 64, gears 66, 68 and 78, shaft 65 and gears 72, 73 to shaft 54. To obtain high 120 speed back gear 66 is thrown out of engagement with the gears on the drive shaft and gear 70 is placed in the solid line position on shaft 65 whereupon the drive will be direct from shaft 62 through gears 71, 70, shaft 65 and gears 72, 73 to shaft 54. Other arrangements of gearing will afford still 125 other speeds. The arrangement shown provides for accuracy in grinding or concaving to a given size for the reason that the motion 130

transmitted from the change gearing to the cam shaft is positive and there is no chance for slippage. This also insures accuracy in grinding the maximum height of crown or 5 the maximum depth of concavity at the longitudinal center of the roll.

The machine is provided with means for changing the position of the cam shaft for either crowning or concaving it or for positioning it to give a maximum crowning 10 effect. Such mechanism comprises a crank (not shown) adapted to be positioned on the reduced end portion 79 of the shaft 54 for turning the shaft in order to cause the 15 worm 53 to turn the worm wheel 52 and the shaft 42 and so change the phase of operation of the cam shaft as to change the action from crowning to concaving or vice versa by change from one of cams 40, 41 to 20 the other, or to maximum crowning by use of cam 40 in the opposite position to that used for concaving. To indicate the correct positions of the cams and the shaft for different effects I have provided a pointer 25 80 on a disk 81 at the outer end of the cam-shaft co-acting with radial lines provided with proper indicia for signifying to the workman when he has turned the crank sufficiently to bring the camshaft into the 30 position for producing the effect desired. At this time the lever 76 must be turned to disengage the gearing and permit the shaft 79 to turn backward.

In order to grind a concave surface on a 35 roll the proper cam shaft speed must be determined and the proper combination of change gears for such speed can readily be found by means of an appropriate gear table showing the necessary arrangement for 40 producing the desired concavity for a given length of work. The wheel carriage 13 is now moved to bring the wheel 17 to a position midway of the length of the roll. In order to set the lift cam 40 which is the 45 cam preferably used in concaving the change gearing must be disconnected by means of the lever 76. The lift cam is now set for concaving by turning shaft 54 with a wrench or crank until the pointer 80 on the cam 50 shaft 42 point to the "concaving" line when the roller 39 will engage heart cams 40 about midway between the apex and the base cleft thereof. In this position the contact line of the cam with the follower 39 55 is midway between its high and low points, the axes of the wheel, the work and the fulcrum lie in the same planes and the grinding wheel is half-way across the surface of the roll.

60 When the grinding operation begins and the wheel carriage starts its traversing motion the camshaft 42 and the cam 40 will begin to revolve thereby moving the grinding wheel 17 above or below the work center 65 just enough to change its relative distance

from the axis of the work sufficiently to produce the desired contour of the work. When the carriage movement reverses the rotation of the cam is also reversed in direction by reason of the connection of the 70 cam shaft 42 to the carriage driving mechanism illustrated in Fig. 3 and the wheel now reverses its path across the roll.

In grinding a concave surface the grinding wheel rises from a position below the 75 work center to a position at an equal distance above the center (or vice versa) while moving from one end to the other and then travels back to its original position of elevation or depression when the carriage 13 80 returns to its original position. In this way the wheel bears with a constant tension on the work, since a line passing through the successive contacting positions of the wheel and the work will lie approximately straight 85 on the face of the work from a position below the horizontal plane passing through the axis of the work and the axis or pivot 38 to a position at an equal distance above said plane. In other words the wheel 90 moves continuously upward in traversing from one end of the work to the other and continuously downward in traversing back to the first-named end of the work instead of moving up for one part of the length of the 95 work and down over the other part. In the latter case, assuming the direction of rotation of the wheel and work to be as indicated by arrows, there will be no change of 100 relative speed at the point of engagement of the two during traverse from one end to the other whereas it will be evident that if the wheel rose during one part of the traverse and descended during the other there would be some lost motion in the drive due to its 105 holding back in the downward action and pulling when raising the wheel which would change the grinding cut slightly with each traverse reversal.

Cam 41 is the crowning cam and when a 110 roll is to be ground with a crown surface by the use of said cam it should be set so that the pointer 80 points to the "crowning" line. The cam being in this position the wheel base is dropped to its lowest point, e. g. a point 115 farthest from the high point of the cam in Fig. 6, it being understood that the distance from the high point varies according to the length of the work. The grinding wheel is now positioned at a point half-way across the surface of the roll. The lift for crowning 120 varies from the lowest point to a point slightly below a horizontal plane passing through the axis of the work. As the carriage moves toward the end of the roll the wheel base, and therefore the grinding wheel, rises to a height determined by the change gear mechanism and as the carriage returns the wheel base descends by reason of the reversing of 125 the movement of the cam shaft until the mid- 130

length position of the roll is reached, the follower 39 now passing the low part of the heart cam and being caused to rise by further rotation of the cam so that the wheel now 5 rises until the carriage is reversed.

The cam 40 is used to obtain the maximum crowning action on a roll, said cam being set so that the pointer 80 points to the line marked "maximum crown." At this time the 10 nose of the cam 40 is in contact with the roller 39 and the grinding wheel is at its highest point and at a point midway of the length of the roll. The movement of the cam 40 in grinding a crown surface is just the opposite 15 of that of cam 41 for grinding a similar surface in that the wheel 17 which has been set at its highest position mid-length of the work moves downward as the carriage moves toward the end of the work, then moves upward as the carriage returns to the middle 20 position and then moves downward again as the carriage passes beyond the mid-point of its traverse toward the other end of the work. It will be recalled that at this time the 25 cam 40 is in the reverse position to that shown in Fig. 5 and oscillates so that the follower 39 moves down the cam in opposite directions from the apex during movements of the carriage to right or left of a point mid-length of the work. In this way the crowning action 30 is increased over that previously described.

It will be obvious to those skilled in the art that various changes may be made in my device without departing from the spirit of the 35 invention and therefore I do not limit myself to what is shown in the drawings and described in the specification but only as indicated in the appended claims.

Having thus fully described my said invention, what I claim as new and desire to secure by Letters Patent, is:

1. A roll grinding machine comprising a grinding wheel, a work holder, means for

causing a relative traverse between them, a base pivoted to permit the wheel to swing tangential to the work, cam followers on the base, a cam shaft having thereon a pair of oppositely positioned cams for each cam follower adapted to be selectively engaged therewith, means for rotating the cam shaft in timed relation with the relative traverse of the grinding wheel and the work carriage and means for varying the speed of rotation of the cam shaft with respect to the relative traverse of the grinding wheel and the work holder whereby the depth of concavity or convexity on the work may be varied in proportion to the length of the work or to cause equal reduction in work of different lengths, substantially as set forth. 60

2. A roll grinding machine including a grinding wheel, a work holder, means for causing a relative traverse between them, a base pivoted to permit the wheel to swing tangential to the work, cam followers on the base, a cam shaft carrying a pair of oppositely mounted cams for each follower, means for causing simultaneous engagement of each follower with a cam of similar form, manually operable means for holding the follower 65 out of engagement with the said cams to permit shifting of the cam follower from one cam to a cam of opposite position, means for rotating the cam shaft in timed relation with the relative traverse of the grinding wheel 70 and the work holder, and change speed gearing for changing the speed of rotation of the cam shaft with respect to the relative traverse of the work holder and grinding wheel, substantially as set forth. 75

In witness whereof, I have hereunto set my hand at Waynesboro, Pennsylvania, this twenty-third day of February, A. D. nineteen hundred and twenty-six. 80

PAUL STONER.
